UNITED STATES PATENT OFFICE.

CARL G. SPRADO, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

FUEL-INJECTION DEVICE.

Application filed June 12, 1920. Serial No. 388,996.

This invention relates in general to improvements in the construction and operation of internal combustion engines, and relates specifically to an improved method of and apparatus for injecting fuel such as oil, into the combustion chambers of engines of the Diesel or similar type.

An object of the invention is to provide an automatic fuel injection device which is simple in construction and efficient in its operation. Another object is to provide a compact and readily accessible structure of fuel injection valves. A further object is to provide a fuel injection device which will effectively atomize fluent fuels and deliver the atomized fuel to the combustion chamber of the engine. Still another object is to reduce to a minimum the cost of construction and operation of fluent fuel injection devices for internal combustion engines.

The invention consists primarily in the provision of a pair of coaxial fluid-pressure-actuated valves located one within the other and adapted to automatically control the flow of fluent fuel through specially arranged passages. The passage controlled by one of the valves is adapted to deliver an axial jet of fluid toward the engine combustion chamber, while the passages controlled by the other valve are adapted to deliver tangential jets of fluid around and toward the axial jet. The jets delivered from the several passages controlled by the valves are directed so that the axial jet flowing at high velocity, impinges against the swirling mass of fluid produced by the tangential jets, thereby effectively atomizing the liquid fuel which is subsequently delivered through an orifice to the combustion chamber of the engine.

The fluid controlling valves are normally urged toward their seats by means of adjustable springs and are lifted by means of the pressure of the fluent fuel acting upon surfaces of the valves. Means are also provided for releasing the fluid pressure thereby positively preventing opening of the valves and stopping the operation of the engine.

A clear conception of an embodiment of the invention and of the manner of operation of the novel fuel injection device, may be had by referring to the drawing accompanying and forming a part of this specifi-

cation, in which like reference characters 55 designate the same or similar parts in the various views.

Fig. 1 is a transverse vertical section through a fuel injection device applicable to an internal combustion engine of the 60 Diesel type.

Fig. 2 is an enlarged fragmentary central vertical section through the delivery portion of the fuel injection device, showing the detailed structure thereof.

Fig. 3 is an enlarged transverse horizontal section through the fuel injection device, the offset fragment of the section being taken near the delivery end of the device along the line III—III of Fig. 2.

The fuel injection device comprises generally, a pair of fluid pressure actuated valves 2, 3, a bushing 4 within which the valves 2, 3 are located, a valve supporting casing 6, a delivery element 10 secured to the casing 6, and a jacket 7 within which the casing 6 is mounted and which serves as a means of connecting the injection device to the cylinder head 8 of an internal combustion engine.

The fluid pressure actuated needle valve 2 is movably mounted concentrically of and within a bore of the sleeve valve 3 and is adapted to control the flow of fluent fuel through the axial passage 32 formed in the 85 valve 3. The needle valve 2 is guided by the sleeve valve bore and is urged toward its seat 31 by means of a compression spring 14 one end of which acts upon the end of a cap associated with the valve and the opposite end of which reacts against an upper inner surface of the sleeve valve plunger 16. The lower end of the needle valve 2 is of reduced diameter thus forming an annular chamber 26 and also providing a valve lifting pressure surface 28 of suitable area.

The fluid pressure actuated sleeve valve 3 is movably mounted concentrically of and within a bore of the bushing 4 and is adapted to control the flow of fluent fuel through the tangential passages 23 formed in the lower extremity of the bushing 4. The sleeve valve 3 is guided by the bushing bore and is urged toward its seat 30 by means of a compression spring 15 one end of which acts upon the upper end of the sleeve valve urging plunger 16 and the opposite end of which reacts against an upper inner surface

of the spring cap 18. The spring cap 18 is secured to the main casing 6 by means of screw threads, thereby providing means for adjusting the tension of the spring 15. The 5 lower end of the sleeve valve 3 is of reduced external diameter thus forming an annular chamber 27 and also providing a valve lifting pressure surface 29 of suitable area. The annular chambers 26, 27 are connected 10 by means of radial conduits 25 formed in the sleeve valve 3.

The bushing 4 is fixedly mounted within a bore of the casing 6, being detachably held within this bore by means of the nozzle element 10. The bushing 4 is provided with diametrically opposite longitudinal recesses 5 which are connected with the annular chamber 27 by means of radial conduits 24 formed in the bushing. The lower extremity 20 of the bushing 4 is cut away to form an annular chamber 22 whereby a connection is established between the recesses 5 and the tangential passages 23. The nozzle element 10 which holds the bushing 4 in place 25 is provided with a discharge orifice 11 located in line with the axial passage 32, through which the atomized fuel is delivered to the combustion chamber of the engine.

The main casing 6 which supports the 30 bushing 4, element 10 and the valves 2, 3 is mounted within the water jacket 7 being secured to the jacket in any suitable manner. The space between the jacket 7 and the casing 6 provides an annular cooling water 35 chamber 21 to which cooling water may be admitted through an inlet pipe 19 and from which the water may be delivered through a discharge pipe 20. The casing 6 is provided with a conduit which connects the 40 fluent fuel supply pipe 9 with the longitudinal recesses 5. A relief port 13 formed in the casing 6 communicates with the atmosphere through a port 17 and is also communicable with the recesses 5 upon opening 45 of the valve 12. The pressure relief valve 12 is manually operable and is opened only when it is desired to prevent operation of the injection device.

During normal operation of the fuel 50 injection device and of the internal combustion engine with which it is associated, fluent fuel is intermittently urged through the inlet pipe 9, recesses 5 and conduits 24, 25 into the chambers 26, 27 by means of a suitable 55 pump not shown. As the pressure of the fuel within the chambers 26, 27 and acting upon the surfaces 28, 29, becomes sufficient to compress the springs 14, 15, the valves 2, 3 are lifted from their seats 31, 30 respectively, and fluent fuel is discharged from the 60 chambers 22, 26 through the passages 23, 32 respectively. The tangential jets delivered from the passages 23 advance along and form a whirling vortex of fluid below the 65 sleeve valve 3. As the axial jet of fluid de-

livered from the passage 32 and flowing at high velocity, strikes this whirling mass of fluid below the valve 3 it produces complete atomization of the fluid. The atomized fuel is urged through the discharge orifice 11 and 70 is delivered into the combustion chamber of the engine in the form of a homogeneous spray. It will be obvious that delivery of fuel to the combustion chamber takes place during each compression stroke of the supply pump. 75

If it is desired to prevent delivery of fuel to the engine combustion chamber, and to thereby stop the engine, it is only necessary to open the relief valve 12 thereby preventing establishment of pressure in the chambers 26, 27 by establishing open communication to the atmosphere. 80

It will be noted that the entire structure is readily accessible for inspection and may 85 be easily dismantled and assembled. The tension of the springs 14, 15 may be quickly varied to adjust the time and the extent of opening of the valves 2, 3. All parts of the structure are readily machinable and may 90 be kept free from accumulation of dirt. The cooling jacket 7 serves to prevent excessive temperatures and the entire operation of the device is automatic. While the valves 2, 3 have been illustrated as vertically disposed, 95 it is obvious that the operation will not be affected by other dispositions thereof.

It should be understood that it is not desired to limit the invention to the exact details of construction and of the operation 100 herein shown and described for obvious modifications within the scope of the appended claims may occur to persons skilled in the art.

It is claimed and desired to secure by Letters Patent:

1. In combination, a main valve having an axis and a discharge orifice concentric with said axis, said axis being surrounded by internal and external seating surfaces, an auxiliary valve coacting with said internal surface to control delivery of fluid from said orifice axially of said main valve, said valves each having actuating means exposed to pressure fluid within the valve chamber to 110 effect the opening of the respective valves by fluid pressure, and means forming a conduit controllable by said main valve and terminating tangentially relatively to a circle 115 circumscribing said axis closely adjacent to 120 said external surface.

2. In combination, a main valve having an axis and a discharge orifice concentric with said axis, said axis being surrounded by internal and external seating surfaces, an auxiliary valve coacting with said internal surface to control delivery of fluid from said orifice axially of said main valve, said valves each having actuating means exposed to pressure fluid within the valve chamber to 125 130

- effect the opening of the respective valves by fluid pressure, means forming a conduit controllable by said main valve and terminating tangentially relatively to a circle circumscribing said axis closely adjacent to said external surface, and means for connecting the valve chamber to the atmosphere to prevent the opening of the valves by fluid pressure.
- 10 3. In combination, a main valve having an axis and a discharge orifice concentric with said axis, said axis being surrounded by internal and external seating surfaces tapering in the same direction and converging toward opposite ends of said orifice, an auxiliary
- 15 valve coating with said internal surface to control delivery of fluid from said orifice axially of said main valve, said valves each having actuating means exposed to pressure fluid within the valve chamber to effect opening of the respective valves by fluid pressure, and means forming a conduit controllable by said main valve and terminating tangentially relatively to a circle circumscribing said axis closely adjacent to said external surface.

In testimony whereof, the signature of the inventor is affixed hereto.

CARL G. SPRADO.
